UNITED STATES PATENT OFFICE.

CHARLES M. GEIGER, OF NEW YORK, N. Y., ASSIGNOR OF ONE-HALF TO ALFRED L. FLYNN, OF NEW YORK, N. Y.

MOTOR-DRIVEN HANSAW.

1,417,726.

Specification of Letters Patent. Patented May 30, 1922.

Application filed June 23, 1920. Serial No. 390,991.

To all whom it may concern:

Be it known that CHARLES M. GEIGER, a citizen of the United States of America, residing at New York, in the county of New York and State of New York, has invented certain new and useful Improvements in Motor-Driven Handsaws, of which the following is a specification.

My invention relates to motor driven handsaws and has for its object to provide in a unitary structure a device of this character which can be readily manipulated and carried from place to place.

Another object of my invention is to simplify the construction and decrease the weight of saws of this general character heretofore in use.

In the accompanying drawings:

Figure 1 is a side view of my invention; 20 and

Figure 2 is a top plan view thereof.

Referring more particularly to the drawings wherein like reference numerals designate corresponding parts in each of the views 25 5 denotes a saw blade of any preferred type such as preference or necessity may dictate.

This saw 5 is bolted to a tubular holder 6 by means of the bolt 7, the holder being screwed into or otherwise detachably connected to one end of a cylindrical plunger 8, operating in a barrel 9 the other end of the plunger being connected to a pitman 10.

The barrel 9 is supported upon one end of a plate 11, or bracket, the other end of which is bolted to an electric motor 12 by means of bolts 13. This motor is formed with a handle 14 to facilitate carrying the device and also for the purpose of properly positioning the saw blade with respect to the 40 piece of work to be sawed.

Mounted upon the driving shaft 15 of the

motor is a pinion gear 19 in mesh with a large gear wheel 16 mounted upon a short shaft 17 projecting upwardly from the plate 11. The pitman 10 is eccentrically attached 45 at its inner end to the large gear wheel 16 by means of a pivot bolt 18. It will thus be seen that rotary movement of the gear 16 is converted into reciprocatory movement in the saw 5 when the plug and cord attachment 20 of the motor is connected to the ordinary electric light fixture and the motor thereby placed in action.

In actual practice the operator after connecting up his motor with a source of current in the manner just described grasps the barrel 9 with his left hand and the handle 14 with his right hand adjacent the guard or collar 21 carried by the barrel 9. The saw blade 5 can thus be moved to a vertical 60 horizontal or inclined position at will according to the nature of the work.

From the foregoing it will be appreciated that I have devised a conveniently operated and efficient portable saw and one which may 65 be economically constructed and handled with safety.

Having thus described my invention:

What I claimed is:

A portable saw comprising an electric 70 motor having a plate secured thereto at its inner end, gearing on said inner end of said plate operatively connected to the motor shaft, a barrel supported on the outer end of said plate, said barrel formed with a 75 hand guard at its extremity, a plunger operating in said barrel and a pitman connecting said gearing with said plunger for reciprocating the same, and a saw secured to said plunger.

In testimony whereof I affix my signature.

CHARLES M. GEIGER.
